UNITED STATES PATENT OFFICE.

MELVIN L. SEVERY, OF ARLINGTON HEIGHTS, AND GEORGE B. SINCLAIR, OF BOSTON,
MASSACHUSETTS.

PULSATION-PRODUCING DEVICE FOR ELECTRICAL MUSICAL INSTRUMENTS.

1,111,866.

Specification of Letters Patent. Patented Sept. 29, 1914.

Application filed July 25, 1907. Serial No. 385,456.

To all whom it may concern:

Be it known that we, MELVIN L. SEVERY, of Arlington Heights, in the county of Middlesex and Commonwealth of Massachusetts, and GEORGE B. SINCLAIR, of Boston, in the county of Suffolk and said Commonwealth, both citizens of the United States, have invented certain new and useful Improvements in Pulsation-Producing Devices for Electrical Musical Instruments, of which

the following is a specification.

This pulsation producing device is designed for use in connection with electric musical instruments wherein tuned sonorous bodies are vibrated by means of properly timed electric pulsations delivered to electromagnets controlling said bodies; and our invention particularly relates to means for grouping and running the toothed members 20 constituting the major part of the device, and to improved means for supporting the brushes co-operating with said members.

The drawing forming part of this specification, is a plan view of our pulsation producing device, with parts thereof broken away in order to more clearly reveal others, and other essential features of the electric musical instrument being shown in diagram.

30 The reference numeral 1 designates the strings or other sonorous bodies vibrated by the electromagnets 2; 4 is the source of current; 3, the keys by which the current is switched to any desired electromagnet, and 35 10, the toothed members, preferably metal rings, composing part of the pulsation producing device for rendering the current properly pulsatory; 20 being the brushes co-operating with said members. As shown in 40 the figure, said members are arranged in groups of twelve in each group, and as many groups as there are octaves in the instrument,—preferably six. It is evident that to have six full octaves it will be necessary 45 for one of the terminal groups to be supplied with one extra ring or member. Otherwise, though, the groups may be exact duplicates; each group containing as many members as there are notes in an 50 octave, and the number of teeth on each member being adapted to the vibrations of some one note of the octave. These groups of mechanically united members are geared one to the next in a way to cause each group 55 to rotate one half as fast as the one next

above it. To do this, the groups are preferably staggered sufficiently to allow a pinion 11 of one group to mesh with a gear 12 of the group next below, of twice its pitch line. Thus the groups will be alike in their gearing also; each group having a small gear at one end and a large gear at the other end. Hence each group of rings or members 10 will produce electric pulsations in numbers per unit of time just an octave below those produced by the group next above it; and the strings 1 vibrated thereby will be similarly an octave below.

We prefer to have the fastest turning group of members the one to receive and transmit power, for the reason that such power if in the slightest degree varied in speed, will have such variations made constantly less noticeable by the repeatedly slower motions of the lower groups. The means by which power is thus imparted to the fastest group consists of the cone and fly-wheel 6, 51, geared thereto; said cone and fly-wheel forming part of any suitable governing device which forms no part of the present invention.

Each group of members can be readily removed from its support by loosening the nuts 15 and raising the spindle from its confining slots 16 in the standards 17. This permits of repairs being quickly attended to should need arise.

Above the staggered groups of members is fixed a bar 21 having oblique lateral faces, for the support of the brushes contacting 90 with the disks 10. These brushes are held by removable blocks 22; a separate block for each group, and the blocks are secured to said bar by the turn buttons 23 projecting through slots 24 in the blocks. By turning 95 said buttons at right angles to their slots, the blocks are fixed in place, while a parallel position permits the blocks' removal.

The circuits through which the electric pulsations made by the make-and-break 100 members 10 are delivered to the electromagnets 2 for the vibration of the strings 1 or other sonorous bodies, comprise the following: From the current source 4, the electricity traverses the wire 32, the framework 105 of the machine to the make-and-break devices, thence through spring contacts 30 and wires 31 of the circuits which have been closed by the depression of keys 3; associated magnets 2, wires 33, contacts 34, 110

brushes 35, and common wire 36 back to said source.

It is evident that, in an instrument constructed with so many parts as is this, it is 5 of the highest importance both mechanically and commercially that there shall be so far as possible a duplication of all similar elements, and a maximum simplification of details inasmuch as a slight complication 10 multiplied a hundred fold will increase the expense and interfere with the renewal and durability of the instrument to a prohibitive extent. One of the most important of such simplifications and duplications is that 15 which we have produced in connection with the above described grouping and staggering of the pulsation producing devices.

Not alone is grouping of members 10 highly important economically, but we find 20 it to be the most practical and efficient way of producing perfectly tuned octaves; since such groups are duplicates of each other, and are all geared together.

Although the disks 10 and gears 11, 12 25 all have their axes in substantially the same horizontal plane, we speak of those nearest the source of power, or cone 6, as above the others because the higher in rank with respect thereto. Hence, in describing the 30 gearing of the said disks or groups of pulsation producing members, we speak in the claims of each being geared to the one next above it to rotate at one half the latter's speed.

35 What we claim as our invention and for which we desire Letters Patent is as follows, to wit:—

1. The combination of tuned sonorous bodies, and electromagnetic means for their 40 vibration embracing a plurality of substantially duplicate groups of rotative pulsation-producing members, and gears rotatively uniting said members, each of said groups having a rotative speed which is either a 45 multiple or submultiple of some one of the other associated groups.

2. The combination of tuned sonorous bodies, and electromagnetic means for their vibration embracing a plurality of substantially 50 duplicate groups of rotative pulsation-producing members, and gears rotatively uniting said members, the speed of

each of said groups, save the slowest, being a multiple of the speed of said slowest rotating group.

3. The combination of tuned sonorous bodies, and electromagnetic means for their actuation having a plurality of substantially duplicate groups of rotative pulsation-producing members geared together to run 60 at relative speeds which are powers of two.

4. The combination of tuned sonorous bodies, and electromagnetic means for their actuation having a plurality of substantially 65 duplicate groups of rotative pulsation-producing members each geared to the one next above it to rotate at one-half the latter's speed.

5. The combination with an electric circuit, of pulsation producing means comprising brushes, and a plurality of substantially 70 duplicate groups of rotative current-affecting members, each group geared to the one next above it to rotate at one-half the latter's speed, and each member of a 75 group being formed with a number of current-affecting elements.

6. The combination with an electric circuit, of pulsation-producing means comprising brushes, and a plurality of substantially 80 duplicate groups of rotative current-affecting members, each group geared to the one next above it to rotate at one-half the latter's speed; the power for driving the same being applied to the fastest rotating 85 group.

7. The combination of tuned sonorous bodies, and electromagnetic means for their actuation having a plurality of substantially 90 duplicate groups of rotative toothed make-and-break members, each group geared to the one above it to rotate at one-half the latter's speed; the power for driving the same being applied to the fastest rotating group.

95 In testimony that we claim the foregoing invention, we have hereunto set our hands this 17th day of July, 1907.

MELVIN L. SEVERY.
GEORGE B. SINCLAIR.
